Application April 17, 1950, Serial No. 156,241

Claims priority, application Great Britain
 April 19, 1949

10 Claims. (Cl. 38—22)

1 This invention concerns improvements relating to garment and like presses, such as are used for hot-pressing in laundries, of the kind comprising a horizontally rotatable carrier with two tables which can be brought in turn into the pressing position. Known presses of this kind comprise a fixed press head and a vertically movable ram by which the table in position is raised to press an article against the head, the tables and head being steam heated. Generally the ram is operated by fluid pressure, whereas the table-carrier is turned by hand. However, it has already been proposed that the carrier should be turned by fluid pressure. Thus, in United States patent application Serial No. 7,628, filed February 11, 1948, it is suggested that the carrier should be turned by fluid pressure always in the same direction of rotation and that the cycle of each individual pressing operation should be separately initiated and automatically completed in response to a single action by the operator, such action consisting in the same operation of a single control device for each cycle. An object of the present invention is to provide a press of the kind set forth which is free from elaborate mechanical linkage or other mechanism.

According to the invention, in a press of the kind set forth, the communication of fluid pressure to both the ram and the carrier-turning means, and also advantageously to other operating elements, is controlled by a selector valve which is moved to one position to initiate the cycle and is moved to another position automatically, in dependence upon the position of the carrier, to complete the cycle. Preferably these movements of the selector valve are effected under the control of a pedal-operated valve and a carrier-influenced valve respectively. Another element which can also be controlled by way of the single selector valve is a clutch-actuating device. A device for returning carrier-turning gear and a pedal-returning device may be controlled indirectly by the selector valve.

One manner of carrying the invention into effect will now be more fully described by way of example and with reference to the accompanying drawings, in which:

Fig. 1 is an elevation, partially in section, of a garment press,

Fig. 2 a section on the line II—II in Fig. 1,

Fig. 3 a vertical section to a larger scale through the selector valve and carrier-influenced valve,

Fig. 4 a vertical section to a larger scale through the pedal-return device,

Fig. 5 an elevation to a larger scale of part of 55 shown in Fig. 3, these ports 24 are uncovered and

2 the rocker, controlling the carrier-influenced valve, as seen from the right-hand side of Fig. 1, Fig. 6 a plan view of the rocker,

Fig. 7 a vertical section to a larger scale through the clutch arrangement, and

Fig. 8 a section on the line VIII—VIII in Fig. 7.

The press illustrated is similar in construction and general operation to that described in the above-mentioned specification and comprises a base 1, a press head 2 and a rotary table carrier 3. The base 1 houses a cylinder 4 for the piston 5 of a ram 6. The head 2, provided with means (not shown) for the circulation of heating steam, is supported from the base 1 by goose-neck 15 columns 7. Two tables 8 are carried in the ends of the arms 9 of the carrier 3 by means of stems 10 which are guided in and extend below the said arms. The carrier 3 is supported by a bearing structure 11 which projects from the base 1 and 20 comprises an arrangement (not shown) for the inlet and exhaust of steam circulated through the tables 8. This arrangement may be of the nature described in the British Patent No. 643,270. An externally toothed ring 12 situated above the 25 bearing structure 11 is connected to the carrier 3.

The control means consists essentially of a selector valve 13 controlling both the movement of the ram 6 and the turning of the carrier 3, as well as other elements as hereinafter described, 30 a pedal-operated valve 14 for causing movement of the selector valve 13 in one direction and a valve 15 operated in dependence upon the position of the carrier 3 for causing movement of the said valve 13 in the opposite direction.

The selector valve 13, conveniently disposed under the cylinder 4, comprises a piston valve (Fig. 3) with a head 16, having bucket leathers 17, directed outwardly and inwardly of the cylinder, at one end and a head 18 possessing a smaller 40 area and having an outwardly directed bucket leather 19 near the other end. The heads 16, 18, with their respective leathers, serve both as driving pistons and also to control ports. An intermediate port-controlling head 20 of the same size 45 as the head 16 has a bucket leather 21 directed towards the head 16, i. e. so as to hold air pressure between the heads 16, 20. A port 22 in the cylindrical wall of the valve and permanently in communication with the air-pressure supply pipe 50 23 opens between the heads 16, 20. A ring of ports 24 located in the said wall and communicating with the cylinder 4 by way of an annular passage 24¹ and duct 24² are controlled by the head 20. In the L. H. end position of the valve 55 shown in Fig. 3, these ports 24 are uncovered and

pressure is communicated to the cylinder 4. In the R. H. end position, the cylinder 4 is connected to atmosphere through exhaust ports 25 and exhaust silencers 26. Communication of pressure to chambers 27, 28 at the ends of the valve through ports 29, 30 is controlled by the valves 14 and 15 respectively, as hereinafter described. There is also a port 31, communicating with a carrier-turning cylinder 32 by a pipe 33 (Fig. 2), which, under the control of the head 18, is connected to pressure via port 29 in the R. H. end position and to exhaust via ports 25 in the L. H. end position. Finally, there is a port 34, controlled by the head 16, which communicates by a pipe 35 with the cylinder 36 of a clutch-disengaging device hereinafter described. A head 37 on the valve co-acts with a resilient pad 37' which serves quietly to arrest movement of the valve to the left.

The pedal-operated valve 14 is a piston valve (Figs. 1 and 2) with two heads 38 having inwardly directed leathers and is loaded by a spring 39. A port 40 communicates with the L. H. end of the selector valve 13 and with the valve 15 by way of a pipe 41 and chamber 42 from which branch connections 43 and 44. A port 45 is connected to the air supply by way of a pipe 46 branched from the duct 23. In the depressed position of the pedal 47, that is with the piston heads 38 in the R. H. end position, the port 40 is in communication with the supply port 45. In the other position of the pedal 47 (Figs. 1 and 2), the port 40 is cut off from the supply port 45 and put in communication with an exhaust port 48. The pedal 47, which is made wide to enable the operator to depress it and, if necessary, restore it from a variety of positions, is coupled to the rod 49 of the valve by a link 50 which passes through a dead-centre position when the pedal is depressed, so that the pedal is held in that position by the action of the spring 39. For automatically tripping the pedal 47, so that it can be restored to its initial position with the assistance of the spring 39, the piston 51 (Fig. 4) of a small return cylinder 52 is arranged to be engaged by the depressed pedal. Pressure air is supplied to the cylinder 52 by way of a pipe 53, as hereinafter described.

The carrier-influenced valve 15 comprises a vertically disposed piston valve (Fig. 3) with a slidably guided upper portion 54, an intermediate downwardly directed bucket leather 55 and a lower portion 56 working through a pot leather 57. The air pipe 44 opens by way of a port 58 into the space 59 between the two leathers 55, 57 and the pressure, when present, urges the valve upwardly against the resistance of a compression spring 60 (Fig. 1) acting on an adjustable push rod 61 which bears on a head 62 of the valve body. The ring of ports 30 communicating with the chamber 28 of the selector valve 13 opens into an annular passage 63. Exhaust is provided for by ports 64. The valve illustrated allows of a large flow of air without the necessity for excessively large ports which would damage the passing leathers, whilst the upward thrust to which the valve is subject is only moderate. However, other arrangements, for example two heads with bucket leathers, but of different areas, could be employed. The valve is normally held in its lowermost position by a rocker 65 which is rotatable about a vertical pivot 66 mounted in the cylinder 4 and which has a hardened pad 67 (Figs. 5 and 6) normally engaged over the adjustable upper end 68 of the push rod 61, which

is guided in a bracket 69. The rocker also carries a block 70 engageable by the hardened end 71 of an adjustable finger 72 carried by a bracket 73 at the end of each arm 9 of the carrier. This block 70 is mounted on a horizontal stem 70' carried by the rocker 65 and can yield slightly thereon against the resistance of springs 70'. The rocker 65 normally occupies the position illustrated in Figs. 5 and 6 in which it is held by a spring 65' which is lodged in a horizontal radial bore in the cover 41 and acts upon a pin 66' projecting downwardly from an arm 65' of the rocker 65 into a vertical bore 67' in the said cover, the movement of the rocker 65 being limited by the freedom permitted to the pin 66' in the bore 67'. The arrangement is such that as a table 8 becomes correctly located over the ram 6, the bevelled end 71 of the finger 72 contacts with a bevel 74 on the block 70 and causes the rocker 65 to turn (clockwise in Fig. 6) just sufficiently to disengage the pad 67 from the end 68 of the push rod 61. During this turning of the rocker 65, the end 71 slides over the bevel 74 until the bevel 74 finally snaps back past the end 71 under the influence of the springs 70'. In the depressed position of the rod 61 and piston valve 15, the chamber 28 at the R. H. end of the selector valve 13 is cut off from the pressure-air supply via 44, 53 and is connected to exhaust via 64. In the uppermost position of the piston valve 15, to which is caused to rise when the push rod 61 is released, the ports 30 are open to the space 59, and pressure can be communicated to the chamber 28 under the control of the pedal-operated valve 14.

The carrier-turning cylinder 32, to which the communication of pressure is controlled from the L. H. end of the valve 13, has working in it a plunger 76 formed with a rack 77 which meshes with a pinion 78. A dog clutch for establishing a driving connection between the pinion 78 and a toothed wheel 79 meshing with the toothed ring 12 of the carrier is operated by a piston 80 (Fig. 7) which works in the cylinder 36 arranged vertically below the pinion 78. The piston 80 serves also as a valve, controlling the communication of pressure to a return cylinder 81 by uncovering a port 82 leading to the latter through a pipe 83 when the piston is in the uppermost or clutch-releasing position. The piston 84 in the return cylinder, also formed with a rack 85 meshing with the pinion 78, in turn controls the communication of pressure via the pipe 53 to the pedal-return cylinder 52 by uncovering a port 86 (Fig. 2).

The dog clutch is arranged so that the dog member is always returned to the correct engaging position after each half turn, wherever the carrier 3 may stop in relation to the ram 6. A suitable arrangement for this purpose is illustrated in Figures 7 and 8. The toothed wheel 79 has a boss 87 held against vertical movement in a fixed housing 88. The shaft 89 of the pinion 78 extends up through the wheel 79 and has an elongated dog member 90 at its upper end engageable with a complementary recess 91 in the wheel. The member 90 is normally held down in the engaging position illustrated in Fig. 7 by a ring of springs 92 acting between the boss 87 and a shoulder 93 on the shaft 89. Formed in the upper part of the housing 88 is an eccentric recess 94 (Fig. 8) into which project the heads 95 of two diametrically opposed plungers 96, 96' slideably radially in the boss 87 and loaded outwardly into contact with the wall of the recess by springs 97. Upon rotation of the wheel 79,

these plungers 96 are caused to move radially in and out in alternation. In the raised, disengaged, position of the member 90, a radial pin 98 secured in a reduced portion of the shaft 89 can engage the inwardly projected plunger 96 which thus serves as a stop.

The arrangement of the eccentricity is such that, when the wheel 79 has completed the anti-clockwise half-revolution in which it drives the carrier 3 clockwise, the plunger against which the pin was last stopped (96¹ in Figs. 7 and 8) is now in the outwardly withdrawn position in which it can offer no obstruction to the clockwise idle return half revolution of the shaft 89 with the dog member 90 in the raised and disengaged position. The other plunger (96), however, is in the projected position and serves as a stop with which the pin 98 comes in contact (chain lines, Fig. 8) at the end of the idle movement. When the clutch is re-engaged, the pin descends out of contact with this plunger which, in the next driving movement, changes positions with the other plunger, the latter in its turn being projected to serve as a return stop, permitting proper re-engagement of the clutch irrespective of the precise position in which the table stops over the ram.

A dash-pot 99 is arranged to control and retard the later part of the driving motion of the plunger 76 in per se known manner.

The manner of operation of the press is as follows: Assume that the carrier 3 is at rest with the ram 6 holding pressure on one table 8 (Fig. 1): The selector valve 13 is to the left, the carrier-influenced valve 15 is held in its lowermost position (both as shown in Figs. 1 and 3), and the clutch 90, 91 is engaged (as shown in Fig. 7). The pedal 47 is now depressed to supply pressure to the chamber 27 at the L. H. end of the selector valve and to the chamber 59 of the carrier-influenced valve by way of pipes 23, 46, ports 45, 40, pipe 41 and branches 43, 44 and ports 29, 58 respectively. As the valve 15 is held down by the rocker 65, however, pressure cannot pass to the chamber 28 at the R. H. end of the selector valve. The selector valve is, therefore, moved to the right, connecting the ram cylinder 4 to exhaust via the ports 25 and then the carrier-turning cylinder 32 to the supply via ports 29, 31 and pipe 33. The ram 6 and the table 8 sink and the carrier is turned through 180° by a drive transmitted from the plunger 76 through the rack 77, pinion 78, shaft 89, clutch 90, 91, and gearing 79, 12. The motion is retarded by the dash-pot 99 and, as the other table 8 comes to rest in position over the ram 6, the rocker 65 is tripped by the finger 72 and the valve 15 is lifted by the pressure in the chamber 59. The snap action already described ensures that the rocker 65 is left free of the finger 72, although it cannot return to its previous position at this stage because it is obstructed by the lifted rod-end 68. Upon the lifting of the valve 15, pressure is communicated to the chamber 28 at the R. H. end of the selector valve 13 which immediately moves to the left (to the position of Fig. 3), as the head 16 is larger than the head 18. The cylinder 32 is cut off from the pressure supply and connected to the exhaust via pipe 33 and ports 31, 25. Pressure is communicated to the ram cylinder 4 via ports 22, 24 and the ram rises and lifts the table. Pressure is also communicated via port 34 and pipe 35 to the clutch cylinder 36 whose piston 80, in rising to release the clutch 90, 91, allows pressure to be communicated

to the return cylinder 81 via port 82 and pipe 83. The piston 84 drives the pinion 78 reversely through the rack 85, thereby returning the piston 76 and clutch part 90 towards their initial positions. At the end of its stroke, the piston 84 causes pressure to be communicated to the pedal-return cylinder 52 via port 86 and pipe 53. The pedal 47 and its valve 14 are returned to their original positions, cutting off both ends 27, 28 of the selector valve 13 and the chamber 59 of the carrier-influenced valve 15 from the pressure and connecting them to exhaust via the port 48. The carrier-influenced valve is returned to the depressed position by the spring 60, leaving the chamber 28 connected to exhaust and freeing the rocker 65 to be returned by the spring 65' to the valve-engaging position shown in Figs. 5 and 6. The whole press is now ready for the depression of the pedal 47 for a fresh cycle of operations.

The arrangement described requires no mechanism for locking the table carrier 3 in position before the ram 6 is raised.

I claim:

1. A garment press comprising a rotatable carrier with two pressing tables, a pressing ram, a fluid-pressure motor for turning the carrier to bring each table in turn into operative relation with the ram, a fluid-pressure motor for actuating the ram, a fluid-pressure supply system, a selector valve connected to the said system and the said motors and arranged directly to control the supply of fluid pressure to both the carrier-turning motor and the ram-actuating motor, an operator-controlled device operatively connected to the said valve for moving said valve to one position for initiating a cycle of operation of the press, a device positioned for operation automatically by the carrier in dependence upon its position and operatively connected to the said valve for moving said valve to another position for causing completion of the said cycle, a carrier-turning gearing connected to the carrier-turning motor, a clutch arranged between the said gearing and the carrier, and a fluid-pressure clutch-actuating motor connected to the selector valve, whereby the communication of fluid pressure to the said clutch-actuating motor is also controlled by the selector valve.

2. A press according to claim 1 and comprising a fluid-pressure motor connected to the carrier-turning gearing for reversely driving the same, the selector valve being connected between the fluid pressure supply system and the said motor, whereby the communication of fluid pressure to the said motor is controlled by the said selector valve.

3. A press according to claim 2, and in which the clutch-actuating motor is connected between the selector valve and the motor for reversely driving the carrier-turning gearing and is arranged also to control the communication of fluid pressure to the latter motor.

4. A garment press comprising a rotatable carrier with two pressing tables, a pressing ram, a fluid-pressure motor for turning the carrier to bring each table in turn into operative relation with the ram, a fluid-pressure motor for actuating the ram, a fluid-pressure supply system, a selector valve connected to the said system and the said motors and arranged directly to control the supply of fluid pressure to both the carrier-turning motor and the ram-actuating motor, an operator-controlled device operatively connected to the said valve for moving said valve to one position for initiating a cycle of operation of the

press, a device positioned for operation automatically by the carrier in dependence upon its position and operatively connected to the said valve for moving said valve to another position for causing completion of the said cycle, a pedal-operated valve and a carrier-influenced valve both connected to the fluid-pressure supply system and to the selector valve, the selector valve being arranged to be moved to the one position by fluid pressure controlled by the pedal operated valve and the other position by fluid pressure controlled by the carrier-influenced valve, and a fluid-pressure motor operatively associated with the pedal-operated valve for restoring it automatically to an inoperative position, the communication of fluid pressure to the said motor being controlled by the selector valve.

5. A press according to claim 4, wherein the motor for reversely driving the carrier-turning gearing is connected between the selector valve and the restoring motor for the pedal-operated valve and is arranged also to control the communication of fluid pressure to the latter motor.

6. A garment press comprising a rotatable carrier with two pressing tables, a pressing ram, a fluid-pressure motor for turning the carrier to bring each table in turn into operative relation with the ram, a fluid-pressure motor for actuating the ram, a fluid-pressure supply system, a selector valve connected to the said system and the said motors and arranged directly to control the supply of fluid pressure to both the carrier-turning motor and the ram-actuating motor, an operator-controlled device operatively connected to the said valve for moving said valve to one position for initiating a cycle of operation of the press, a device positioned for operation automatically by the carrier in dependence upon its position and operatively connected to the said valve for moving said valve to another position for causing completion of the said cycle, a pedal-operated valve and a carrier-influenced valve both connected to the fluid-pressure supply system and to the selector valve, the selector valve being arranged to be moved to the one position by fluid pressure controlled by the pedal-operated valve and to the other position by fluid pressure controlled by the carrier-influenced valve, and a rocker engageable with the carrier-influenced valve for normally holding the latter in a position in which it cuts off fluid pressure from the selector valve, the said rocker being engageable by a part of the carrier and movable thereby to release the former valve so that it can be moved by fluid pressure to a position in which it passes fluid pressure to the latter valve.

7. A press according to claim 6, and in which the carrier and the rocker are engageable by means of snap-action parts, one of which parts

is adapted for moving quickly past the other as soon as the rocker has been moved to release the valve.

8. A garment press comprising a rotatable carrier with two pressing tables, a pressing ram, a fluid-pressure motor for turning the carrier to bring each table in turn into operative relation with the ram, a fluid-pressure motor for actuating the ram, a fluid-pressure supply system, a selector valve connected to the said system and the said motors and arranged directly to control the supply of fluid pressure to both the carrier-turning motor and the ram-actuating motor, an operator-controlled device operatively connected to the said valve for moving said valve to one position for initiating a cycle of operation of the press, a device positioned for operation automatically by the carrier in dependence upon its position and operatively connected to the said valve for moving said valve to another position for causing completion of the said cycle, a carrier-turning gearing connected to the carrier-turning motor, a clutch arranged between the said gearing and the carrier, and a fluid-pressure clutch-actuating motor connected to the selector valve, whereby the communication of fluid-pressure to the said clutch-actuating motor is also controlled by the selector valve, the clutch being a positively acting clutch and comprising stop means for locating one part of the disengaged clutch for correct re-engagement with the other part at the end of idle return movement of the carrier-turning gearing.

9. A press according to claim 8, and in which
35 the clutch-locating means comprises an abut-
ment associated with the part of the clutch con-
nected to the carrier-turning gearing and en-
gageable, in the disengaged condition of the
clutch, alternately with alternately retracted and
40 projected stops associated with the part of the
clutch connected to the carrier, the said stops
being arranged to be incapable of engagement
when the clutch is in the engaged condition.

which the clutch is in the engaged condition.

10. A press according to claim 9, and in which the retraction and projection of the stops is controlled by an eccentric annular track over which the said stops are moved with the clutch part connected to the carrier.
